UNITED STATES PATENT OFFICE

JAMES M. JACKSON, OF ST. LOUIS, MISSOURI

ROLL PAPER SUPPORT

Application filed July 20, 1929. Serial No. 379,757.

This invention relates to improvements in holding brackets for roll paper, the primary object of the invention being to provide a support for roll paper, such as toilet tissue or paper toweling, which will permit a partial rotation of the roll to allow a fixed quantity of the paper to be removed therefrom.

Another object of the invention is to provide a supporting bracket of the above described character which will, to a certain extent, compel economy in the use of the paper by permitting only a certain amount to be unrolled every time a pull is exerted upon the free end of the roll, this pulling operation of the end of the roll partly rotating the same and after separating the strip of paper removed from the roll a reverse rotation thereof takes place to rewind any remaining hanging portion.

The invention will be best understood from a consideration of the following detailed description taken in connection with the accompanying drawing forming a part of the present invention, with the understanding, however, that the invention is not confined to any strict conformity with the showing of the drawing but may be changed or modified so long as such changes or modifications mark no material departure from the salient features of the invention as expressed in the appended claim.

In the drawings:—

Figure 1 is a view in vertical central section of the paper holder embodying the present invention.

Figure 2 is a view in front elevation of the holder, per se.

Referring more particularly to the drawings wherein like numerals of reference indicate corresponding parts throughout the several views, the numeral 1 indicates generally the paper roll supporting bracket for the present invention which bracket, as shown, is preferably formed of a single piece of sheet metal of proper width and comprises a back plate 2, preferably of elongated rectangular formation and the turned forwardly projecting side plates 3, each of which has the lower forward portion obliquely cut away, as indicated at 4, so that the forward

edge 5 of each side plate is materially shorter than the rear portion of the plate.

Each of the side plates 3 has formed therethrough adjacent the forward edge 5 and at the lower part thereof an aperture 6 which is designed to receive one end of a rod 7 which forms a part of the paper roll holding member, indicated as a whole by the numeral 8.

The member 8 comprises a relatively narrow metal plate 9 of sufficient length to position comfortably between the side walls 3 of the bracket and the rod 7 which is of greater length than the plate 9, is secured along one side edge thereof, as shown.

The method preferred for securing the rod to the plate is to roll over the edge of the plate wrapping the rod therein.

At the opposite side edge the plate is rolled over a rod 10 similar to the rod 7, this rod 10 being of greater length than the plate 9, normally hanging therefrom free from contact with any part of the bracket.

In placing a paper roll in position for support by the bracket, the usual cardboard cylinder forming the center of the roll is distorted slightly so as to be of elliptical cross sectional design to receive the holder member 8. By distorting the cylinder of the paper roll and then placing the holder member 8 therein the roll will grip the holder as a result of its tendency to return to its original circular form and thus be firmly attached thereto. The side members 3 of the bracket are then spread sufficiently to admit insertion of the ends of the rod 7 into the apertures 6, the roll being so positioned that the free end will unwind from the side adjacent the back plate 2 of the bracket.

From the foregoing description taken in association with the accompanying drawings it will be readily seen that when the roll 11 has been placed in position as described it will swing freely between the side plates 3 upon the supporting rod 7 and when a portion of the paper is desired the end thereof is pulled down which operation will partly rotate the roll and the rod 7 swinging the rod 10 upwardly until the ends thereof are brought into contact with the forward edges 5 of the walls 3. Further rota-

tion of the roll is then prevented and the amount of paper withdrawn can then be easily separated from the roll following which operation the roll will swing down to its former position and draw up the free end of the paper.

Any appropriate means may be employed for securing the bracket to a wall or other supporting structure, there being here shown screw members 12 which are passed through apertures formed in the back wall 2, in the manner shown.

Having thus described my invention, what I claim is:—

15 A holder for paper rolls having a tubular core comprising a pair of plates designed to be mounted in spaced parallel relation to project forwardly from a supporting surface and each having a substantially vertical forward edge and further having an aperture formed therethrough adjacent the lower part of the forward edge, and a roll supporting body comprising an elongated plate adapted to position between the side plates and having a bar extending longitudinally of each side edge and projecting beyond the ends thereof, one of said bars being designed to have its ends extended through said apertures, the other of the bars 20 limiting rotary movement of the holder and roll through contact with the forward edges of the side plates.

In testimony whereof I hereunto affix my signature.
